UNITED STATES PATENT OFFICE.

ARTHUR L. WITTENMYER, OF KIRKLAND, WASHINGTON.

HOT-PLATE LIFTER.

1,375,268.

Specification of Letters Patent. Patented Apr. 19, 1921.

Application filed June 30, 1919. Serial No. 307,606.

To all whom it may concern:

Be it known that I, ARTHUR L. WITTENMYER, a citizen of the United States, residing at Kirkland, in the county of King, State 5 of Washington, have invented certain new and useful Improvements in Hot-Plate Lifters; and I do hereby declare the following to be a full, clear and exact description of the invention, such as will enable others 10 skilled in the art to which it appertains, to make and use the same.

This invention relates to culinary utensils and more particularly to an improved device for lifting hot plates or the like.

15 The primary object of the invention is to construct a novel device of the above character of general utility around a kitchen or bakery for removing hot pies from an oven, the device consisting of two curved gripping 20 arms terminating at the rear end in two closing handles and supplied on top with a lifting handle for transporting the pie to any desired place after it has been drawn from the oven and the device being formed 25 of wire bent in a novel manner so as to render the device capable of quick and economical production.

With the above objects and others in view as will appear as the specification proceeds, 30 the invention comprises certain novel combinations and arrangements of parts as will be hereinafter more particularly pointed out and claimed.

In the drawing like reference characters 35 refer to corresponding parts, the figure being a perspective view of my improved hot plate lifter. Referring to the drawing in detail, the device is shown as comprising a pair of opposed curved gripping arms 10 and 11 40 each similarly constructed of a single section of wire or the like bent intermediately as shown at 12 to provide bight portions directed outwardly substantially at right angles at the free ends of the jaws comprising spaced top and bottom portions 13.

At the rear end of the spaced top and bottom portions 13 forming the concavely articulate jaws for receiving and holding a plate or the like, the rebent portions of the section 50 or strand of wire, are intertwined as shown at 14, being also directed outwardly immediately in front of the twisted portions forming the shanks of the handles, as shown at 15. Said intermediate twisted portions are 55 also formed with loops or eyes 16 for receiving a rivet or other like pivot 17 so as to

dispose the handles one upon the other in cross relation for pivotal movement to grip or release the plate. Beyond said twisted portions, the rebent portions of the strand 60 or section of wire are extended upwardly and downwardly so as to provide opposed vertical handles 18 having spaced top and bottom portions rebent in opposite directions at their ends as shown at 19 and each 65 end is formed with a terminal eye 20 bent at right angles to envelop or receive the other end portion 19 therethrough adjacent to its point of bending. This provides an effective means for anchoring the terminals and providing gripping handles to permit effective clamping of the object between the jaws of the device.

However, in order to facilitate the gripping and lifting operation, the upper portion 75 13 of each jaw is provided intermediately with an upwardly and inwardly curved shank portion 21 the sides of which are inter-twisted and which are formed with terminal eyes 22 extending upwardly. To these eyes 80 are connected the lower looped extremities 23 of the crossed levers 24 of a lifting handle. The levers 24 are formed of single sections of wire intertwined intermediately as shown at 25 and formed with eyes 26 for receiving 85 a connecting pivot 27, loops 28 being formed at the upper ends of the jaws at the handle portions thereof for receiving the fingers in order to facilitate the clamping of the plate and lifting thereof after the plate has been 90 engaged in the jaws of the holder in the manner already described.

It will thus be seen that I have provided a 95 very simple and economical device for lifting hot plates and the like and which by reason of the jaws being formed of outwardly directed end portions, results in the provision of pockets for effectively receiving the edge of the plate or other circular object clamped therebetween as well as to prevent 100 displacement vertically of the jaws with respect to the plate so that as long as the handles are normally held together at the gripping portions thereof, the plate will be positively held until it is desired to release 105 the same.

What is claimed is:—

1. A hot-plate lifter comprising horizontally extending pivoted handles having plate engaging jaws with spaced top and bottom portions and a lifting handle extending transversely of the jaws and comprising 110

pivotedly connected levers which are each loosely connected at one end with one of the jaws connected to said jaws.

2. A hot plate lifter comprising a gripping element having pivoted jaws, each including spaced top and bottom portions, said top portions having inwardly extending stems, and a lifting handle comprising pivoted levers connected to said inwardly extending stems, the pivoted levers being in a plane transversely to the pivoted jaws.

3. A hot plate lifter comprising pivoted handles having jaws with spaced top and bottom portions, said top portions, having inwardly extending portions and a lifting handle comprising pivoted levers connected to said inwardly extended portions and formed with loops at their upper ends, as and for the purposes specified.

4. A hot plate lifter comprising pivoted handles each formed of a single section of material bent intermediately to provide spaced top and bottom portions and then intertwined, the remaining portions being spaced apart to form handles extending vertically and having the ends thereof disposed in over-lapped relation at right angles to said spaced portions and formed with terminal eyes engaging the respective over-lapping portions adjacent to the spaced portions.

5. A hot plate lifter comprising pivoted handles each formed of a single section of material bent intermediately to provide spaced top and bottom portions and then intertwined, the ends of the rebent portions being extended upwardly and downwardly in spaced relation substantially parallel to each other and then bent at right angles and inter-connected, to brace said portions in spaced relation and anchor the terminals of said rebent portions.

6. A hot plate lifter comprising pivoted handles each formed of a single section of material bent intermediately to provide spaced top and bottom portions and then intertwined, the ends of the rebent portions being extended upwardly and downwardly in spaced relation substantially parallel to each other and then bent at right angles and inter-connected to brace said portions in spaced relation and anchor the terminals of said rebent portions and a lifting member comprising pivoted levers connected to the upper portions first mentioned.

7. A lifter of the class described comprising handles having jaws with spaced top and bottom portions and end portions directed outwardly, said handles being pivoted intermediately and formed at their opposite ends with gripping portions vertically disposed, said top portions having inwardly extending portions offset upwardly and finger gripping levers pivoted to said inwardly extended portions.

8. A hot plate lifter comprising a pair of handles each formed of a single section of resilient wire bent intermediately to provide bight portions directed outwardly and opposed concaved jaws having top and bottom portions and outwardly directed rear ends, the remaining portions being intertwined and formed with intermediate eyes, a pivot engaged through said eyes, the remaining ends being extended in spaced relation and inter-connected to form gripping portions, said top portions having their intermediate portions intertwined and formed with terminal loops extending upwardly and lifting handles comprising single sections of wire intertwined and having terminal eyes engaging said loops, and intermediate eyes, and a pivot engaged through said eyes to pivotally connect the handles in crossed relation, the intermediate portions of the lever sections being bent to form loops at the upper ends thereof, as and for the purposes specified.

9. A hot plate lifter comprising a pair of handles each formed of a single section of resilient wire bent intermediately to provide bight portions directed outwardly and opposed concaved jaws having top and bottom portions and outwardly directed rear ends, the remaining portions being intertwined and formed with intermediate eyes, a pivot engaged through said eyes, the remaining ends being extended in spaced relation extended in divergent relation to provide opposed vertically alined top and bottom portions with the ends thereof bent at right angles and secured in over-lapping relation.

In testimony whereof, I affix my signature, in the presence of two witnesses.

ARTHUR L. WITTENMYER.
